S. E. PRITCHARD,

FAN BLOWER.

APPLICATION FILED SEPT. 24, 1915.

1,184,992.

Patented May 30, 1916.

SAMUEL E. PRITCHARD
INVENTOR

BY Thomas R. Harvey

ATTORNEY.

UNITED STATES PATENT OFFICE.

SAMUEL E. PRITCHARD, OF MOON RUN, PENNSYLVANIA.

FAN-BLOWER.

1,184,992.

Specification of Letters Patent.

Patented May 30, 1916.

Application filed September 24, 1915. Serial No. 52,387.

To all whom it may concern:

Be it known that I, SAMUEL E. PRITCHARD, a citizen of the United States of America, residing at Moon Run, in the county of Allegheny and State of Pennsylvania, have invented certain new and useful Improvements in Fan-Blowers, of which the following is a specification.

The present invention relates to improvements in fan blowers, designed especially for use in impelling air currents for sanitation and ventilation in mines, restaurants, hotels, theaters, and other public or similar places.

15 The primary object of the invention is to improve the construction of the fan blower in several particulars to render it more efficient in enlarging the volume of air currents impelled therefrom, without the expenditure of added power and without additional cost which will affect the operation of the fan to any appreciable extent.

20 The invention consists in certain novel combinations and arrangements of parts as hereinafter set forth and claimed.

In the accompanying drawings I have illustrated one complete example of the physical embodiment of my invention constructed according to the best mode I have 25 so far devised for the practical application of the principles of my invention, and this embodiment has proven highly efficient and satisfactory in actual service.

Figure 1 is a side elevation of the fan blower, showing its bearings, but omitting its housing for convenience of illustration. Fig. 2 is a sectional view of the blower or impeller, on line 1—1 Fig. 1. Fig. 3 is an end view of the impeller or blower, the 30 bearings being omitted. Fig. 4 is a detail view showing a collar on the blower shaft with the inner ends of the louvers attached thereto. Fig. 5 is a detail of a central brace for the fan blades. Fig. 6 is a diagrammatic view showing the fan blower in its housing.

The blower is preferably located in a horizontal position for best results, and in this form the invention is illustrated with 35 a central shaft 1 supported in its bearings 2, 3, and the shaft is revolvable in the journal bearings.

There are nine blades designated by the 40 numeral 4 arranged to extend longitudinally of the shaft with their inner ends or edges 1 on the periphery of the shaft and

tangential thereto with the edge of each succeeding blade overlapping the preceding one and forming a closed pocket at the inner or shaft end of the blade.

As best seen in Fig. 1 the blades are of 45 tapered formation, *i. e.* they are longer at their inner ends than at their outer ends, and at their sides the edges are curled as at 5, 5. The maximum depth of this curl or 50 curve to the sides of the blades is at the outer end, and the curl or curve diminishes as the blade approaches the shaft so that the extreme inner edge of each blade lies flat upon the shaft as described.

The blades are supported between two 55 side rings 6 and 7 by means of two sets of cross bars 8 and 9 which have their bent ends fastened as by rivets to the curled side edges of the blades as at 10 and to the rings 6 and 7 as at 11 respectively. Thus the 60 front brace bar 8 holds the curled side edges while the rear brace bar supports the blade between the two rings 6 and 7 and is itself supported between and braces the two rings. 65 A central tangentially slotted disk or collar 12 is fastened on the shaft to brace the blades by angles 12'.

The rings 6 and 7 are rigidly held and supported from the shaft by means of two 70 series of louvers 13 and 14, which are riveted at the inner sides of the respective rings 6 and 7, at their outer ends, and at their 75 inner ends the louvers are riveted as at 15 to a collar 16 at one end of the blower, and 80 a second collar 17 at the other end of the blower. The louvers are each located at the side of the curled edge of a blade, and it will be seen that they are fashioned as 85 pockets or cups with outwardly flaring walls 85 approximately parallel with the tapered curled edge of the sides of the blades. These 90 pockets are not closed however, but the flaring louver and the outer side of the curled blade edge, between them, form a space 95 through which the air is trapped and passed to the succeeding blade as the fan blower 100 revolves. In this manner the air is scooped or caught by the flaring louvers at each end of the fan and guided around the outer side 105 of the curled edges of the blades and caught by the succeeding blade which impels the air through the duct 18 of the housing 19 in Fig. 6. By the utilization of the flaring 110 louvers and the curled edges of the blades a greater quantity or volume of air is trapped, and the curled edges of the sides

115

of the blades prevent escape of air at the sides of the fan and in this manner the capacity of the blower is increased as the volume of impelled air is increased.

5. What I claim is:—

In a fan blower the combination with a shaft, of blades extending therefrom having curled side edges, spaced rings with supporting connecting bars for the blades and brace

bars connecting the curled edges of each 10
blade, a louver attached to a ring at the
curled edge of each blade for guiding air
currents to the succeeding blade, and the
inner end of each louver connected with the
shaft.

In testimony whereof I affix my signature.

SAMUEL E. PRITCHARD.
